CONSTRUCTION OF HANDLES

Noel Ray Stiles, Billingshurst, England

Application May 28, 1936, Serial No. 82,359
In Great Britain May 30, 1935

12 Claims. (Cl. 12—144)

The object of this invention is to construct a handle for use with vacuum carpet cleaners and other articles, in an improved manner.

My invention comprises a handle for use with 5 vacuum carpet cleaners and other articles constructed in sections, capable of being rigidly held together or disconnected for reducing the length for easy carriage and storage, some sections being formed with tubular edges connected by a 10 flat web or webs, an end or the ends of one or more sections being provided with coupling means projecting from the tubular portions for engaging with the tubular portions of another section or sections, and means for temporarily securing 15 the sections to the projecting coupling means, a grip portion or another section constructed as of a curved or other shaped strip or strips secured together, having one end constructed to form coupling means or with coupling means applied, a 20 semi oval or half-round strip secured to each side of the curved or other strip for a portion of its length, a tubular length of india rubber or like material surrounding the grip section means for securing same to the grip portion, and a further 25 section constructed from a curved bar or bars having means at one end for attachment to a carpet sweeper or other article, the other end or ends being so constructed as to be connectable to a section and means for temporarily holding it 30 thereto.

My invention will be clearly understood from the following description aided by the annexed drawings in which:—

Figure 1 is a side elevation, and Figure 2 a 35 front view of a complete handle with the sections assembled.

Figure 3 is a side elevation of a handle with the sections disassembled.

Figure 4 is a side elevation of a section having 40 tubular edges, but without projecting coupling means.

Figure 5 is a section on the line V, V of Figure 4.

Figure 6 is a section on the line VI, VI of Figure 4.

45 Figure 7 is a section on the line VII, VII of Figure 4.

Figure 8 is a side view of a tubular edged section partly in section, and showing the projecting coupling means in position at one end.

50 Figure 9 is an end view of the section shown in Figure 8 and showing the projecting coupling means.

Figure 10 is a section on the line X, X of Figure 8.

55 Figure 11 is a perspective elevation of a portion

of one of the lengths of metal for forming a section.

Figure 12 is an elevation, and Figure 13 a part sectional edge view of a coupling device.

Figure 14 is a side view, and Figure 15 an 5 edge view, and Figure 16 a side view, all partly in section of the grip section.

Figure 17 is a sectional view on the line XVII, XVII of Figure 14.

Figure 18 is a section on the line XVIII, XVIII 10 of Figure 14.

Figure 19 is a section on the line XIX, XIX of Figure 14.

Figure 20 is a side elevation of a curved flat strip or strips of the grip section. 15

Figure 21 is a section on the line XXI, XXI of Figure 20.

Figure 22 is a side view of a curved semi-oval strip positioned on the strip shown in Figure 20.

Figure 23 is a section on the line XXIII, XXIII 20 of Figure 22.

Figure 24 is a perspective view of a screw threaded holed plate fitting recesses in the end of the curved strip shown in Figure 20.

Figure 25 is a view of the cap on the free end of 25 the grip section, and Figure 26 a view of a ferrule fitted on the grip section.

Figure 27 is a front view, partly in section, and Figure 28 a side view of the section attachable to a vacuum cleaner. 30

Figure 29 is a section on the line XXIX, XXIX of Figure 28.

Figure 30 is a section on the line XXX, XXX of Figure 27.

Figure 31 is a front view, and Figure 32 a plan 35 of one of a half tube encircling the members attached to a vacuum cleaner.

Figure 33 is a front elevation of one of the curved bars attached to a vacuum cleaner.

Figure 34 is a side view of a plate positionable 40 between the curved bars.

Figure 35 is a plan of a curved strip positionable under and secured to the curved bars and engaging the strip shown in Figure 34.

Figure 36 is a plan of a vacuum cleaner with 45 a portion of a handle attached.

Figure 37 is a side view, and Figure 38 an edge view of the handle attachment plate.

The handle may be formed in any number of sections, and I will describe same as applied to 50 four sections.

As shown on the drawings the two centre sections A, B as at Figures 4 to 13 are each formed of two lengths of metal formed by stamping and bending or otherwise, with a semi-circular or ar- 55

cuate portion 1 along its length having a flat web 2 extending from each edge, the webs 2 being engaged with each other, see Figure 7, and secured together by welding or otherwise, thus forming a section having two tubular edges 1 with the combined webs 2 between. At one end of each section, or both ends of one section, I position and secure in the end or ends of the section a coupling means comprising a double plate 4, each 5 stamped with parallel semi-circular ribs 5 and secured together with the ribs 5 coinciding on the outside, and such ribs 5 extend at 5^a to outside one end of the plate to form extensions, and this plate is positioned inside one or both ends 10 of a section A or B, with the extensions 5^a projecting therefrom, and such plate is secured inside the section, and a hole 6 is provided near its outer end corresponding with a hole 7 in the end of the next section to which this section is 15 to be joined, the hole on one side of the other section being surrounded by a screw boss, so that on the insertion of the extensions 5^a into the end of the next section, the two sections can be rigidly clamped together by a screwed bolt 9 20 being passed through the holes 7, 6 and engaging the screw boss 8, or I may employ separate coupling means or the like having a portion projecting from the section, and near the other end I form a hole completely through the webs 2, and 25 surrounding each hole on one side I form a semi-circular recess in each tubular portion and opening into same, and in each hole I pass a screw bolt provided with a washer, which is of a diameter to engage the recesses in the tubular portions 30 and grip the coupling means, the screw bolt engaging a screw threaded hole in the webs or a nut positioned on the other side of the webs.

The handle grip portion or third section as at Figures 14 to 26 is made from a curved flat strip 40 10 formed preferably from two pieces of metal secured together (or it may be straight or other formation) having at one end a projecting portion 10^a of slightly lesser width, and such piece of metal has ribs 10^b, 10^b formed therewith and 45 projecting outside when the pieces are secured together, such combined ribs 10^b, 10^b fitting the tubular portion of a section, and at the other end two different sized recesses 11, 11^a, and to this flat strip is welded or otherwise secured on 50 each side a curved or bulged strip 12, 12 semi-oval or half-round in cross section, such strips 12, 12 being positioned on the flat strip so that they coincide with the recessed end and are slightly away from the reduced width portion at the other 55 end, but covering a portion of the ribs 10^b.

In the larger recessed end and within the larger recess 11 is secured a plate 13 having a screw threaded central hole, such plate 13 having extensions 13^a which fit holes 14 in the strips 12 60 and can be secured thereto.

To the flat strip at the reduced width end, I position a ferrule 15, and I affix to the reduced end 10^a of the strip 10 a short length 16 of a section constructed as previously described and 65 thus holding the ferrule in position so that it rests against the ends of the outside strips 12, and at the other end of the section 16, I may apply the coupling ribs 5.

On the combined elements forming the hand 70 grip portion or section, I position a tubular length of india rubber or like material 17 which forms the outside of the grip portion and fits the elements with one end engaging the ferrule 15, and the other end about flush with the end of the 75 handle, and on this end I position a cap 18 which

engages the ends and is provided with a central hole, so that by application of a screw 19 to said hole and the screw threaded hole in the plate 13 in the end, the cap 18 and outside grip portion 17 can be held to the hand grip portion, and the 5 screw may be provided with a ring or hook.

The fourth section, see Figures 27 to 35, is connected to the means or is constructed with means to which the handle can be connected to the 10 vacuum carpet sweeper or other article.

In constructing this section, I employ two bars 20, each being curved or angled at one end 20^a and carrying means such as projecting pins 21, 22, one 21 for engaging slots 23 in plates 23^a on the sides of the cleaner for propulsion purposes, and the other 22 for engaging a hole 24 when not required for propulsion purposes. Each bar 20 is then curved at right angles to an arcuate shape as at 20^b and then straight as at 20^c, so that when the two bars are positioned with their straight 20 surfaces adjoining, the remainder form a fork for its ends to embrace the sweeper.

In joining the two bars 20 together, the straight portions 20^c have a strip 25 positioned between them for a portion of their length leaving the 25 straight surfaces projecting in parallel order, and the strip 25 has a hole 25^a at one end for receiving a curved strip 26 which has recesses 26^a on opposite edges to engage the walls of the hole 25^a, and such curved strip 25 when positioned fits under 30 the bottom of the curved portions 20^b of the bars 20 and is welded thereto.

At the top of the strip 25 is positioned a collar 27 forming a base to the parallel extensions 20^c, and these parallel extensions are shaped somewhat like a dumb bell for embracing one of the sections A or B when connected thereto and further held by a bolt 9 (Fig. 36) being passed through the section and holes 20^d in the straight portions 20^c. Surrounding the upper curved portions 20^b of the bars and the straight portions up to the collar 27 on each side, is a channel device 28 fitting the straight portions 20^c to the strip 25 and over the upper curved portions 20^b of the bars 20 and turned down under the curved plate 26, 45 each device 28 being riveted at 29 to the straight portions 20^c and strip 25 next the collar 27, thus forming a protection and strengthening device to the section.

In assembling the sections, the fourth section is 50 connected to the one of the two centre sections by the straight portions 20^b being passed outside the other section B and embracing same, and the other centre section A is applied to this section B by its coupling means engaging the tubes in the 55 section A, and the hand grip portion is applied the same way to the other end of the last applied centre section; the bolts 9 are then engaged and tightened up to hold all the sections rigidly together, when the handle can be applied to a 60 sweeper or other article.

To dismantle the handle, the bolts 9 are loosened and removed and the sections pulled apart, and for storage or carriage, the sections are positioned one next to the other, greatly reducing 65 the length, and instead of employing four sections, any number of sections each constructed in accordance with one of the two centre sections A, B may be employed.

In applying the invention for use with an electric operated apparatus, say an electric carpet 70 sweeper, the hand grip portion and the end portion may be provided with electric plugs, and the sections provided with plugs and sockets on the inside, electrically insulated and connected with 75

wires contained in the sections, hand grip and end portion, so that when the sections are positioned together, the electric contacts can be made at the same time, and when in use the plugs in the handle grip portion may be connected with a socket in a wall, and the plugs at the end connecting the sweeper connected with the socket controlling the motor, but the electric wiring may be effected in any other manner, and a switch may 5 be provided on the hand grip portion.

What I do claim as my invention and desire to secure by Letters Patent is:—

1. A handle for use with vacuum cleaners and other articles constructed with its stem in sections 15 capable of being rigidly held together or disconnected, each section for forming the length or stem being formed from two lengths of metal shaped with a semi-circular tubular portion with a flat web extending from each edge of the semi- 20 circular portion, the webs being engaged and secured together, projecting means from this semi-circular or tubular portion on the end of certain sections for engaging within the tubular portion of another section, means for temporarily 25 securing the section to the projecting means, a hand grip portion comprising strips secured together and having an end piece at one end and projecting means on the other end for engaging the tubular portions of a section, means for 30 securing the projecting means to the tubular portions, a curved forked frame having means at the two forked ends for connection to the vacuum cleaner or article, and projecting means on the outside and centrally of its length for connection 35 to a section forming the length or stem, the sections forming the length or stem being connected together with the hand grip at one end and the vacuum cleaner or other article at the other end.

2. In a handle construction, two strips having 40 midportions arcuate in cross section forming edge portions, webs in spaced relation extending from each edge portion, said webs being secured together in overlapping relation with one web disposed between the webs of the other strip, said 45 edge portions providing channels for engagement by an adjacent handle section.

3. In a handle construction, two strips having midportions arcuate in cross section forming edge portions, webs in spaced relation extending from 50 each edge portion, said webs being secured together in overlapping relation with one web disposed between the webs of the other strip, and a coupling for engagement with an adjacent handle part, said coupling extending between said strips 55 and having portions disposed in said edge portions.

4. In a handle construction, two strips having midportions arcuate in cross section forming edge portions, webs in spaced relation extending from 60 each edge portion, said webs being secured together in overlapping relation with one web disposed between the webs of the other strip, said edge portions providing channels for engagement by an adjacent handle section, said webs having 65 aligning openings therethrough, and screw threads in one of said openings for engagement by a fastening screw.

5. In a handle construction, two strips having midportions arcuate in cross section forming edge 70 portions, webs in spaced relation extending from each edge portion, said webs being secured together in overlapping relation with one web disposed between the webs of the other strip, said edge portions providing channels for engagement 75 by an adjacent handle section, said webs at one

end of the device being spaced apart and having aligning openings therethrough for fastening of an adjacent handle part, said webs having aligned openings therethrough, and screw threads in one of said openings for engagement by a fastening 5 screw.

6. In a handle construction, a flat strip, outwardly bulged strips disposed against opposite faces of the flat strip, a tubular cover about said strips, a plate interfitted with one end of the flat 10 strip, interengaging fastening means between the plate and adjacent end portions of the bulged strips, and means engaged with the plate to secure the cover in place.

7. In a handle construction, a flat strip, outwardly bulged strips disposed against opposite faces of the flat strip, a tubular cover about said strips, a plate interfitted with one end of the flat 15 strip, the flat strip having a notch at one end in which said plate is seated, lugs on said plate 20 engaging openings in the bulged strips, a cap disposed over the ends of the bulged strips and flat strip, and means fastening the cap to the plate.

8. In a handle construction, a flat strip, outwardly bulged strips disposed against opposite faces of the flat strip, a tubular cover about said strips, a plate interfitted with one end of the flat 25 strip, interengaging fastening means between the plate and adjacent end portions of the bulged strips, and means engaged with the plate to secure 30 the cover in place, said flat strip comprising contacting members having portions extending beyond the first mentioned strips and provided with ribs for engagement with an adjacent handle part.

9. In a handle construction, bars having 35 straight portions, a spacing strip therebetween spaced from terminal ends of the bars so that they may constitute attaching tines, said bars having portions extending outwardly adjacent the strip and collectively forming a fork for engagement with an implement, a strip contacting and reinforcing said portions and interfitted with the first strip.

10. In a handle construction, bars having 45 straight portions, a spacing strip therebetween spaced from terminal ends of the bars so that they may constitute attaching tines, said bars having portions extending outwardly adjacent the strip and collectively forming a fork for engagement with an implement, a strip contacting and reinforcing said portions and interfitted with the first strip, and reinforcing structure enclosing said 50 bars adjacent the locations of said strips.

11. In a handle construction, bars having 55 straight portions, a spacing strip therebetween spaced from terminal ends of the bars so that they may constitute attaching tines, said bars having portions extending outwardly adjacent the strip and collectively forming a fork for engagement with an implement, said strip having an opening, a strip extending through said opening and having notches engaging the walls at said opening, the second strip contacting and reinforcing said portions, a collar resting on the first 65 strip and through which the tines pass, and reinforcing channel devices engaging the collar and enclosing said strips and adjacent portions of the bars.

12. In a handle construction, a flat strip, outwardly bulged strips disposed against opposite faces of the flat strip, a tubular cover about said strips, a plate interfitted with one end of the flat 70 strip, interengaging fastening means between the plate and adjacent end portions of the bulged 75

strips, and means engaged with the plate to secure the cover in place, said flat strip comprising contacting members having portions extending beyond the first mentioned strips and provided with ribs for engagement with an adjacent handle part, said adjacent handle part comprising two strips having portions arcuate in cross section,

webs in spaced relation extending from each edge portion, said webs being secured together in overlapping relation with one web disposed between the webs of the other strip, said edge portions providing channels receiving said ribs.
